Primary Examiner—Louis S. Zarfus
Assistant Examiner—Frank Martinez**[57] CLAIM**

The ornamental design for a rear window license plate holder with swivelling suction cup attachment members, as shown and described.

DESCRIPTION

FIG. 1 is a front elevational view of the rear window license plate holder with swivelling suction cup attachment members showing our new design;

FIG. 2 is a rear elevational view thereof;

FIG. 3 is a right view thereof;

FIG. 4 is a left view thereof;

FIG. 5 is a top plan view thereof;

FIG. 6 is a bottom plan view thereof; and,

FIG. 7 is an isometric view thereof.

The broken line showing of vehicle license plate is for illustrative purposes only and forms no part of the claimed design.
